UNITED STATES PATENT OFFICE.

Olie Johnson, of Belview, Minnesota.

TIME-SHEET.

SPECIFICATION forming part of Letters Patent No. 714,188, dated November 25, 1902.

Application filed March 6, 1902. Serial No. 96,896. (No model.)

To all whom it may concern:

Be it known that I, Olie Johnson, a citizen of the United States, residing at Belview, in the county of Redwood and State of Minnesota, have invented certain new and useful Improvements in Time-Sheets; and I do hereby declare the following to be a full, clear, and exact description of the invention, such as will enable others skilled in the art to which it appertains to make and use the same.

My invention has for its object to provide an improved time card or sheet so marked that a permanent and accurate record may be quickly made; and to the above ends the invention consists of the novel devices and arrangement of parts hereinafter described, and defined in the claim.

In accordance with my invention I provide a space in which the name of each employee may be written, and in line with each of such spaces I provide a series of dials, there being one dial for each working day of the week and Sunday included, if desired. These dials are marked in graduations indicating the hours of the day and preferably, also, of fractions thereof, at least to the extent of half-hours. The dials are in the best arrangement also provided with secondary index-lines, which make more prominent the marks indicating "12 o'clock M.", "7 o'clock A. M.", and some other hour, such as "5 o'clock P. M." The two latter secondary marks afford a V-shaped space in which may be conveniently written the numeral indicating in hours and fractions thereof the amount of work done by a particular employee during that day.

My invention is illustrated in the single view of the drawing and in which numeral 1 indicates the time card or sheet ruled by horizontal lines 2, which afford spaces at the left in which the names of the employees may be written. At the right of these spaces vertical lines 3 cross the lines 2 and cut the sheet into a series of squares, in which squares are located so-called "dials." At the tops of the vertical columns of dials are letters indicating the days of the week. The dials are indicated as entireties by the numeral 4, and it will be noted that the same are divided by graduations which indicate hours and half-

hours. A long radial graduation-mark 5 is run from the dial to the mark indicating "12 o'clock M.", and likewise two other long 55 graduation-marks 6 and 7, respectively, extend from the center of the dial to the marks indicating "5 o'clock P. M." and "7 o'clock A. M."

At the right of the dials the sheet is ruled 60 and marked to afford spaces in which may be written the total time for the week in hours, the rate per hour, the total amount, and the time when paid. These latter features may be dispensed with, but are nevertheless 65 convenient and desirable. It will be noted that a space is left between the columns of dials indicated by T and W. This is simply because the sheet is intended to be folded or bound on that line or in that space. 70

The manner of using the time-card will become evident from an inspection of the irregular pen-marks on the dials and the data placed at the right and the numerals placed in the spaces between the diverging index-marks 75 6 and 7. To illustrate, suppose Ed Jones, the first workman indicated on the time-sheet, begins work at seven o'clock Monday morning, works until noon, takes an hour for dinner, and then begins at one o'clock p.m. and 80 works until six. To indicate this time, the dial is marked as shown on the dial at the top of the column appropriated on Monday and marked with a large letter "M." Then at night, to make the record more certain and 85 more conveniently read at sight, the numeral "10" is written on the said dial in the space afforded between the radial marks 6 7. This same sort of record is kept up throughout the week, and at the end of the week the total 90 time is marked at the right of the series of dials in the space provided therefor.

As is evident, but very little time is taken during the day in keeping a record of the working time of a large number of employees, 95 as the person keeping the time need only, when a particular workman starts to work, to start a mark indicating the time and then complete the mark when the workman quits, so as to cover the time which he may have 100 worked. I myself have in practical experience found this time-sheet a great time-saver to the employer as well as a very convenient and accurate device for keeping time-records.

The time-sheet described is of course capable of modifications within the scope of my invention as herein set forth and claimed.

What I claim, and desire to secure by Letters Patent of the United States, is as follows:

A time sheet or card marked with the horizontal lines 2 and vertical lines 3 cutting the same into a plurality of rectangular spaces and affording other spaces in which the names of the workmen may be written, and provided with dial - graduations within said former noted spaces involving the radial secondary

index-lines 5 extending to the mark indicating noon, and the radial marks 6 and 7 extending, respectively, to marks indicating certain hours p. m. and a. m., substantially as and for the purposes set forth.

In testimony whereof I affix my signature in presence of two witnesses.

OLIE JOHNSON.
